CHARLES WALCOTT STRATFORD, OF OAKLAND, CALIFORNIA

FILM HEATER AND VAPORIZER

Application filed February 8, 1928. Serial No. 252,757.

This invention relates to improvements in a method and apparatus for heating fluids, and refers more particularly to the impinging of fluids in a plurality of jets against the exterior of a curved surface and heating the shallow film of fluid formed by the impingement of said fluid surrounding the curved surface.

Among the salient objects are: to provide a method and apparatus for heating fluids in which the heater consists of telescopic tubes forming a closed annular containing space for the fluids, and a heat supply, or means for heating the interior or inner tube, the fluid being introduced and impinged against the heated surface of the inner tube, whereby a circulation or rapid movement of the film of fluid is produced, aiding materially in removing the heat, thereby transmitting the heat more rapidly to the fluid; to provide also an apparatus whereby the heat exchange between the fluid undergoing heating and the combustion gases, is substantially instantaneous; and in general, to provide a method and apparatus hereinafter described.

Figure 1 is a diagrammatic side elevational view of the heater with parts broken away.

Figure 2 is a view taken along the line A—A in Figure 1.

Figure 3 is a sectional side view of a pre-heating apparatus to be used in connection with the heater.

Figure 4 is a top section of the preheater furnace, shown in Figure 3.

Figure 5 is an enlarged detail of the connections to the annular space between the telescopic tubes.

Figure 6 is a diagrammatic side elevational heater connected into a system for heating oil.

Referring to the drawings, the heater consists of two cylindrical vessels 1 and 2, having diameters slightly different and placed one within the other to form an annular space 3, therebetween. The outer sheet or tube has formed therein, protrusions 4, which serve as connections to the discharge leads 6 the inlet leads 5 being connected directly to the outer shell 2. The inlet leads

are connected to inlet laterals 7 running longitudinally of the cylindrical vessels 1 and 2, and these laterals 7, in turn, have connection, through pipes 8, with the ring headers 9. Connected to the ring headers, is a distributing header 10 supplied with fluid through the discharge line 11 of the pump 12. In brief, then, the supply distributing circuit consists of a pump 12, driven by a motor 13, supplying fluid through the line 11, to the header 10, thence to the distributing ring headers 9 from which the fluid is supplied to the laterals 7 through the connections 8 and finally through the jets 5 to the annular space between the inner and outer cylindrical vessels.

Similarly, there is a discharge circuit, consisting of withdrawal leads 6, connecting into the laterals 14, which, in turn, have connection with the ring headers 15. These ring headers have communication through the pipes 16, with the header 17, from which a single discharge line 18, furnishes a means for withdrawing or removing the fluid after heating, from the system.

The thickness of the annular space 3, between the telescopic tubes may vary according to the character of the material which is being heated and its susceptibility to the transmission of heat. At the extremities of the inlet leads 5, there are preferably positioned nozzles such as that described in connection with the circulatory system of my Patent No. 1,613,298, issued January 4th, 1927. These nozzles spread the liquid in a thin film upon the inner curved heated surface and produce a rapidly moving layer of oil in all directions, over the inner heated surface from the separate nozzles. The inlets of the discharge pipes 5 and 6 are arranged and positioned over the surface of the outer shell so as to produce a relatively continuous sheet of rapidly moving fluid over the inner heated curved surface.

To heat the interior of the vessel at one end of the inner tube is a burner such as that diagrammatically shown at 19. The combustion gases from the burner travel longitudinally of the inner tube and are exhausted or discharged through a duct or flue 20 which

is preferably heavily insulated as shown at 21. This duct is connected up with a flue discharge pipe which leads to a chimney or stack, not shown. Within the enlarged duct 20, is heat exchanging surface in the form of a sinuous coil or pipe 22.

In operation, fluid is supplied from any convenient source through pump 12 and the pipe 11, where it is preheated by the combustion gases discharged from the exhaust end of the tube 1, shown in Figures 4 and 6. Instead of passing first through a preheating section such as the pipes 22, the fluid may be charged direct to the heater through the pump 12 from any suitable source, as shown in Fig. 1. Where a preheater is used, the preheated fluid is discharged then, through the line 11, into the header 10, thence through the leads 8 to the laterals 7, by means of which it is distributed to the inlet pipes 5. At the extremities of the inlet pipes or where the fluid is discharged into the annular space between the cylinders 1 and 2, there are distributing nozzles which impinge the fluid traveling at high velocity, onto the inner curved heated surface, this inner cylinder being highly heated, immediately or substantially instantaneously, transmits its heat to the film of fluid traveling rapidly over its surface. The fluid is then discharged at high velocity through the pipes 6, in the laterals 14, and headers 15, to the leads 16 and discharge headers 17 and pipe 18, through which it is delivered to separating and fractionating apparatuses of any suitable type, according to the fluid which is being heated.

The method and apparatus is adapted to use in the heating of petroleum hydrocarbons, coal tar distillates, in the distillation of water in steam boiler practice, and for innumerable other uses in connection with the heating or distillation of liquids or fluid materials. It is particularly useful in the distillation of lubricating oils where rapid heat exchange and distillation are desired without decomposition, and in this connection the heater lends itself to use in vacuum apparatus.

The rapidity of heat exchange and the efficiency of the method by which the heat of the combustion gases is taken up by the rapidly moving film, permit the burning of the fuel at the best possible or optimum conditions of combustion. The separate distributing circuit introduces the fluid discharged by impingement onto the heated curved surface, at decreasing velocities which promotes equalization of the fluid distribution at the point of impingement.

The apparatus shown in Figure 6, discloses the use of the heater as applied to an oil distilling system maintained either under atmospheric or substantially atmospheric conditions of pressure or under high vacuum.

The heated fluid is discharged from the heater through the pipe 18 and passes through an adjustable valve 25, interposed in the extremity of the line, or at the point where the vapors are introduced to the combined vapor liquid separator and circulating pump 26. This vapor liquid separator consists of an outer shell upon which is mounted a motor 27. Within the shell is a depending cylinder 28, open at its lower end. The upper end of the cylinder is attached to the upper portion of the casing. The vertical shaft of the motor 29 extends the length of the separator and has mounted near the lower end thereof, a centrifugal pump rotor diagrammatically shown at 30. The discharge from the pump is designated in the drawings as 31 and communicates with the line 11 by means of which the oil, unvaporized in the separator 26, is returned to the heater. A secondary withdrawal line 32, connected into the line 31, serves to remove portions of the liquid bottoms from the system. This latter line is controlled by a diaphragm operated valve 33, automatically manipulated by means of the liquid level control device 34, affixed to the side of the separator. A take-off vapor line 35 is connected into the inner cylinder 28 and communicates with the fractionating tower 36 into which the vapors evolved from the liquid in the separator are led over, to the fractionating tower, where they are subjected to refluxing action. Controlled fractionation is practised in the tower 36 and overhead vapor is taken off through the line 37 and directed to the condenser 38, passing thence through the line 39, in the form of distillate, to the gas separator 40. Liquid accumulating in the bottom of the fractionating tower, is taken off by the draw-off line 41, regulated by the valve 42, either automatically or manually.

When the system is operated under vacuum, a barometric condenser may be interposed in the line 39 and the vacuum pumps 43 and 44 put into operation.

When vacuum is not being used, the liquid and vapor drawoff lines 45 and 46, may be used. A steam line is connected into the bottom of the vapor liquid separator 26. As suggested, the heated fluid discharged from the film evaporator or heater, passes through the line 18 and is discharged through the orifice or adjustable valve 25, tangentially into the vapor liquid separator 26. The fluid spirals downwardly through the separator, the liquid clinging to the inner surface due to the centrifugal force of the vapor accumulation in the vortex or in the central portion of the chamber. This vapor rises through the open-ended pipe 28 passes out through the vapor pipe 35, into the fractionating or dephlegmating column 36. In this latter column, there is refluxed, the still vaporized portion passing overhead through

the line 37 to the condenser 38 and accumulating as distillate in the gas separator 40. The liquid, unvaporized in the vapor liquid separator, accumulates and is discharged by the pump rotor 30 through the line 31, back to the heater through lines 24 and 11. Simultaneously, there is withdrawn, a regulated portion of the tar bottoms, through the line 32, the amount of withdrawal being controlled by the liquid level device 34.

The injection of steam through the line 47, accelerates the evolution of vapors in the separator and improves the character of the final distillation, preventing to a great extent, decomposition.

Decomposition is further prevented by the use of vacuum and the rapidity at which the heat is transmitted to the oil in the film evaporator.

Data from the cracking art shows clearly that chemical decomposition of hydrocarbons, by heat, is greatly influenced by the period of time during which oils are held at high temperatures. In most heaters, now available, the liquid volume capacity divided by charging flow rate through the heater gives a time factor that is many times too large to avoid a soaking effect and cracking. Unquestionably, there is an urgent need of equipment in which oil may be heated to desired terminal temperatures within an extremely short period of time. The ideal system would be one in which the temperature of distillation could be reached in a period of a few seconds, vaporization then accomplished in a zone of lowest possible hydrocarbon pressures, to keep down terminal temperature, and a system in which the distillates are rapidly cooled after fractionation or separation.

The heater described, comprises a firing tube against the outer surface of which the oil to be heated is impinged. Surrounding the firing tube is placed a concentric collector tube enclosing a thin annular space of small total volume for the flow of oil, manifolding for the uniform distribution of oil, from the discharge of the circulating pump, to the nozzles, is attached to the outer shell as is also the manifolding for receiving the heated oil as it is forced from the annular space through slots and passes directly to the vaporizer. The circulating pump, being incorporated in the vaporizer, receives the separated oil discharging a portion from the system and sending the remainder back through the heater with the fresh feed. Energy put into the circulating pump is usefully expended in imparting desired high velocity to the sheet flow of oil over the heating surface. All of this surface 'sees' the fire and transfers heat at a uniform rate. The firing tube can be easily withdrawn for inspection. It is evident that charging rate to this heater does not influ-

ence velocity of oil over the heating surface though it does change the time factor.

Examining the principal causes of failure of heat absorption by liquids we find nothing that cannot be easily corrected. The entire transfer surface should be swept by a continuous sheet of liquid moving at high velocity in most complete and intimate contact with it. This flood of liquid must be of sufficient quantity to furnish an adequate medium for absorbing all the heat transmitted. Immediately after contact with the heating sheet the oil should be allowed to freely evaporate. Liquid flow at high velocity assures perfect cleanliness on the oil side of the sheet, guarantees lowest oil film temperatures, and prevents the accumulation of silt, carbon or salt films having high heat insulating properties. The heat absorbing capacity of oil vapors or of these vapors mixed with atomized oil is many times lower than that of liquid oil. From this fact it follows that a heating surface can only be sufficiently protected from failure by the sweep of liquid oil, when this surface, on the fire side, is directly exposed to absorption of radiant heat at high temperature levels and at high specific rates. The present system fulfills all requirements of highest transfer rates.

I claim as my invention:

1. An apparatus for heating fluids comprising telescopic plain surfaced tubes forming a closed annular containing space for the fluids, means for heating the interior of the inner tube, and means for discharging by vertical impingement against the exterior of the inner tube the fluid to be heated to produce a sheet flow in predetermined circulation areas at the heated surface.

2. An apparatus for heating fluids comprising telescopic tubes forming a closed annular containing space for the fluids, means for heating the interior of the inner tube, a plurality of jets for discharging by impingement against the exterior of the inner tube the fluid to be heated to produce a continuous sheet flow over defined circulation areas at the heated surface, and supply lines and withdrawal lines from said containing annular space.

3. A method of heating fluids comprising the steps of impinging the fluid upon a tube heated from within in a plurality of unbroken liquid jets projected vertically over predetermined circulation areas to produce a sheet flow of relatively uniform depth adjacent the curved heated surface, and heating the shallow film of fluid formed by the impingement thereof against the tube.

4. A method of heating fluids comprising the steps of impinging the fluid against the exterior of a heated tube through a plurality of liquid jets projected vertically onto the heated surface, said jets positioned at prede-

5 terminated points on the curved surface to produce a continuous sheet flow of uniform distribution, and removing the fluid at a plurality of predetermined points arranged to maintain a series of defined circulation areas upon the heated tube.

10 5. An apparatus for heating fluids comprising spaced telescopic tubes forming a closed annular heating surface for fluids to be heated, means for heating the interior of the inner tube, means in close proximity to the heated surface for discharging by impingement fluid against the curved surface thereof, said means positioned at a plurality 15 of points and arranged to create an equalization of fluid distribution, and withdrawal means for removing the heated fluid at a plurality of points arranged to maintain defined circulation areas of the sheet flow produced 20 by the travel of the fluid from the impingement means to the withdrawal means.

25 6. An apparatus for heating fluids comprising spaced telescopic tubes forming an enclosed annular containing space for the fluids between the tubes, means for heating the interior of the inner tube, a plurality of jets uniformly distributed on the exterior of the outer tube and adapted to supply the liquid to be heated by vertical impingement 30 against the exterior of the inner tube to produce a continuous sheet flow thereover, and withdrawal lines from the containing annular space.

35 7. An apparatus for heating fluids comprising spaced telescopic tubes forming a closed annular containing space between the tubes for the fluids, means for heating the interior of the inner tube, jets and withdrawal lines uniformly distributed on the external 40 surface of the outer tube whereby the fluid is impinged simultaneously at a plurality of points against the inner tube, setting up a sheet flow over defined circulation areas at the transfer surface.

45 8. An apparatus for heating fluids comprising spaced telescopic tubes forming a closed annular containing space for the fluids, means for heating the interior of the inner tube, inlet jets and discharge ports distributed over the surface of the outer tube 50 whereby the fluid to be heated is circulated in a continuous sheet flow over defined circulation areas, at the heated surface.

CHARLES WALCOTT STRATFORD.
